HENRY E. CURTIS, OF SAN JOSE, CALIFORNIA, ASSIGNOR OF ONE-HALF TO JOHN H. BETTS, OF LONG BEACH, CALIFORNIA

INTERNAL-COMBUSTION ENGINE

Application filed May 5, 1927. Serial No. 189,084.

The present invention relates particularly to the manifold of an internal combustion engine.

It is one object of the invention to provide a manifold so constructed and arranged as to effect the complete and thorough homogenization of the combustible mixture passing therethrough.

It is another object of the invention to provide a manifold wherein the combustible mixture is passed in effective heat exchanging relationship with exhaust from the engine cylinders whereby to effect its more perfect vaporization.

It is still another object of the invention to provide a device of the character indicated that will be simple in form and construction, economical to manufacture, and highly efficient in its practical application.

20 In the drawing:

Figure 1 is a plan view of a manifold embodying my invention, part being broken away.

Figure 2 is a sectional view on 2—2 of Figure 1.

Figure 3 is a section on line 3—3 of Figure 1.

Figure 4 is a section on line 4—4 of Figure 2.

30 Referring now more particularly to the drawing, I show at 1 a casting having the following characteristics. Since the manifold is symmetrically formed, the detailed description of one-half of the structure applies equally well to the other half.

In the present embodiment of the invention the discharge end of the exhaust lies in a vertical position as shown at 2 and branches upwardly and outwardly as at 3

40 and 3a, the two branches forming a basin 4 for the purpose hereinafter set forth. At 5 is shown a continuation of the branch 3 and extending horizontally therefrom. The exhaust from the engine cylinders is 45 discharged into the passage 5 through side openings 6 and 7. The passage 5 is preferably of much greater width than height so that the heating effect of the exhaust gases may be utilized to the fullest extent.

50 Cast on the upper surface of the branch

3 and spaced but a little way therefrom is a top wall 8. This wall overlies the branch 3 in substantially parallel relation thereto to form a wide shallow chamber 9. This chamber converges at the end adjacent the engine as at 10, dropping downwardly to the horizontal plane bisecting the passage 5 and provided with an opening 11 adapted to communicate with the valve chamber of the engine, not shown. The other end of the chamber curves downwardly as at 12 into angular communication with the basin 4. Above the basin 4 and in axial alignment therewith is formed a passage 13 through which the combustible mixture is introduced from a carburetor not shown. The carburetor is mounted upon the surface 14.

That portion of the chamber into which the fresh mixture is introduced lies parallel with the plane of the openings 6, 7 and 11, but in order to communicate with the discharge opening 11 its outer wall is made arcuate in form as shown at 15. This portion of the chamber bounded on the outer side by wall 15 is divided into four channels 16, 17, 18 and 19 by means of three arcuate webs 20, 21 and 22 as shown.

When the manifold is mounted upon an engine in full operation the exhaust enters through openings 6 and 7, passes through the passage 5 and discharges through 2, while the fresh mixture enters chamber 9 through 13 and 12, is divided into four independent streams throughout the length 80 of the webs 20, 21 and 22, and then combines again into a single stream flowing through passage 10 and opening 11 into the valve chamber of the engine.

It is obvious, of course, that the heated 90 gases passing out through the exhaust passages will heat the walls thereof and parts connected to said walls. By making the passage 5 quite wide in proportion to its height a large heated floor area is provided for the chamber 9, the webs 20, 21 and 22 being also heated by conduction.

When the fresh mixture is drawn into chamber 9 through passage 13, inertia carries the heavier particles down into the 100

basin 4 while the more perfectly vaporized mixture moves directly into passage 12. Since the basin is effectually heated by the exhaust gases impinging thereupon from both sides, the heavier material gathering therein is quickly vaporized and sucked up into the stream moving into passage 12. In the chamber 9 the vaporization of the mixture is still further advanced by the heated walls enclosing it. The centrifugal force generated in the flowing gaseous mixture as it travels through an arc to opening 11 would ordinarily separate the heavier particles of liquid still remaining therein from the remainder of the mixture and cause it to collect along the outer curved wall 15. I obviate this difficulty by dividing the mixture up into four small streams, thereby accelerating its speed of movement and securing complete, positive and final vaporization of all the heavier particles still remaining in the mixture through contact with the heated webs.

It may now be readily seen from the foregoing disclosure that I have provided a structure in which the exhaust and the fresh mixture are moved in opposite directions to each other and in heat exchanging relationship to each other in such a manner that a combustible mixture passed through the manifold is discharged therefrom in perfect condition for use.

The channels 16, 17, 18 and 19 have their floors dropped a distance below the general level of the floor of chamber 9 whereby to receive and hold all moisture that may collect in the channels at various times, to deliver the same when the heat and suction is sufficient to remove it these lowered floors are indicated at 23, 24, 25 and 26. It is also pointed out that the ribs 20, 21, 22 are continued a distance in to the straight portion of the chamber 9 so the channels may receive the mixture before any centrifugal action has been developed.

It is to be understood, of course, that while I have herein shown and described but one specific embodiment of the invention, changes in form, construction, arrangement and operation of the several parts and features may be made within the scope of the appended claim.

I claim:

In combination, an exhaust manifold for internal combustion engines, and an intake manifold for the same mounted upon and overlying the exhaust manifold with a common wall therebetween, the said intake manifold extending lengthwise of the exhaust manifold a distance and then curving laterally to discharge at right angles thereto, the said intake manifold having a plurality of vertical webs formed in its curved portion to divide the same into a plurality of independent channels, terminating at

points beyond the curved portion at both ends, the bottoms of the said channels being depressed below the general level of the bottom of the intake manifold to serve as receptacles for liquid fuel.

HENRY E. CURTIS.
